US00D944830S

(12) **United States Design Patent** (10) **Patent No.:** **US D944,830 S**
(45) **Date of Patent:** **** Mar. 1, 2022**

(54) **DISPLAY SCREEN OR PORTION THEREOF WITH GRAPHICAL USER INTERFACE**

(71) Applicant: **Lutron Technology Company LLC**,
Coopersburg, PA (US)

(72) Inventors: **Shilpa Sarode**, Allentown, PA (US);
Bryan R. Barnes, Lansdale, PA (US)

(73) Assignee: **Lutron Technology Company LLC**,
Coopersburg, PA (US)

(**) Term: **15 Years**

(21) Appl. No.: **29/734,692**

(22) Filed: **May 14, 2020**

(51) LOC (13) Cl. **14-04**

(52) U.S. Cl.

USPC **D14/486**

(58) **Field of Classification Search**

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with graphical user interface showing the claimed design.

The peripheral dashed broken lines illustrate a display screen or portion thereof and form no part of the claimed design.

1 Claim, 1 Drawing Sheet

(1 of 1 Drawing Sheet(s) Filed in Color)
